UNITED STATES PATENT OFFICE.

JOHN H. ELWARD, OF POLO, ILLINOIS.

PORTABLE-ENGINE FURNACE.

SPECIFICATION forming part of Letters Patent No. 276,874, dated April 24, 1883.

Application filed October 20, 1882. (No model.)

To all whom it may concern:

Be it known that I, JOHN H. ELWARD, a citizen of the United States, residing at Polo, in the county of Ogle and State of Illinois, have invented certain new and useful Improvements in Portable-Engine Furnaces, of which the following is a specification, reference being had therein to the accompanying drawing.

In the drawing there is shown a longitudinal section of a portable engine and furnace embodying my improvements.

C represents the fire-flue, the rear part, D', of which is utilized as the furnace.

D² is the hearth-plate, provided with hooks d³ at the inner edge for supporting the grate-bars d, which at their rear ends are supported in seats d², formed on the bridge-wall D³. At the front end of the furnace there is a door adapted for the admission of either coal or light fuel, it consisting of an outer part, F², an inner part, F, and a lower portion, F'. The part F is hinged to the part F², and provided with a weight, X, which tends to return it to an upright position.

C is the rear smoke-chamber, and C² the front chamber, the rear chamber being formed between the rear end wall, a, and the partition c at the rear end of the water-space, and the front chamber, C², being formed between the front partition, c', for the water-space and the front end walls, B B'.

The fire-flue extends from the rear outer wall, a, to the front partition, c'. Below the hearth-plate D² there is an aperture, E', extending from the furnace through the outer shell. Farther in from the rear end, and inside of the rear end of the water-space, there is another aperture, E², the sheet by which it is surrounded being inclosed by water, as shown at a². Below these apertures there is an ash-pan, E, having inclined swinging doors e² at the ends and supplemental sliding doors E' at the sides.

Upon the platform there is supported a receptacle, E⁷, to receive cinders or other material, which may pass out through the lower door, F', said receptacle having a sloping mouth, as at e⁷.

At the front end there is a water-jacket con-

structed of an under plate, G², an inner plate, G, an upper plate, G', and an outer plate, B'. 50

In the bottom of the front smoke-chamber, C², there is an aperture for the escape of ashes, cinders, &c., which aperture is closed by a door, P'. Said materials pass into a receptacle at P, which is pivotally supported 55 upon the axle of the front wheels.

e is a sliding door, by means of which the inner aperture, E², is closed. Preferably this door is moved by means of a rod extending through the rear end of the furnace, though 60 other means may be used.

Under some circumstances it is very desirable to have a copious admission of air into a furnace of the character described directly below the grate-bars, and with air-passages 65 arranged in the manner shown this can be readily effected. When the doors e² for the withdrawal of ashes are closed, air can be admitted to the passage E² through the sliding doors E', and the amount thereof can be read- 70

I do not in this application claim anything but what is specifically set forth in the following claims, reserving to myself the right to claim all other patentable matters in another 75 application heretofore filed of which this is a division.

What I claim is—

1. In a portable engine, the combination of the furnace-chamber, a substantially horizontal grate therein, a door in the front end below said grate, an ash-pan below and independent of the furnace-chamber, the ash-exit E', communicating with said ash-pan, a supplemental aperture communicating with said 85 ash-pan and the furnace-chamber, a door for opening and closing said supplemental air-passage, and means extending to the outside of the furnace for operating said door, substantially as set forth. 90

2. In a portable engine, the combination of the following elements, namely: an outer cylindrical boiler-shell, an inner fire-flue shell, the water-space formed by said shells and by the transverse partitions c c', the smoke-chamber C at the rear end around the fire-flue 95

shell outside of the water-space, the ash-pau
outside of and independent of the furnace-
chamber, the opening E' below the smoke-
chamber and outside of the water-space, the
5 opening E² inside of the water-space and sur-
rounded by the water, and the horizontal grate
situated above said opening E², substantially
as set forth.

In testimony whereof I affix my signature in
presence of two witnesses.

JOHN H. ELWARD.
